UNITED STATES PATENT OFFICE.

RALPH ERNEST JONES, OF THE UNITED STATES ARMY.

ELECTRIC BULLETIN.

1,390,039.

Specification of Letters Patent. Patented Sept. 6, 1921.

Application filed August 8, 1918. Serial No. 248,930.

To all whom it may concern:

Be it known that I, RALPH E. JONES, a citizen of the United States, and a major in the United States Army, have invented certain new and useful Improvements in Electric Bulletins, of which the following is a specification.

My invention relates to improvements in electric bulletins, and it consists in the constructions, combinations and arrangements herein described and claimed.

An object of my invention is to provide an electric bulletin whereby information in the possession of an individual may be disseminated among a large number of persons either by day or by night.

Another object of the invention is to provide an electric bulletin including a bulletin board capable of being used in either of two embodiments for night or day use, the characters on the bulletin board in either instance being formed by the manipulation of a transmitter of the same construction.

Other objects and advantages will appear in the following specification reference being had to the accompanying drawings in which:

Figure 1 is a diagrammatic view showing the general arrangement of the electric bulletin, including a portion of the bulletin board, the transmitter and the wiring.

Fig. 2 is a diagrammatic view showing the mechanism employed in the lighting of the lamps to form the character "E."

Fig. 3 is a sectional view shown partly in diagram and illustrating one of the magnetic switches and the wiring connections for one of the reflectors.

Fig. 4 is an elevation of a portion of the bulletin board showing the arrangement of the reflectors comprising one of the character frames.

Fig. 5 is a diagrammatic plan view of a portion of the transmitter showing the arrangement of the contact rollers on the character wire bars, and how the character cylinders are rotated upon the depression of a key of the transmitter.

Fig. 6 is a detail sectional view on the line 6-6 of Fig. 5.

Fig. 7 is a perspective view of one of the character cylinders.

Fig. 8 is a detail view of one of the transmitter keys.

Fig. 9 is a detail view of a portion of the

bulletin board showing the arrangement of one of the character units when the board is employed for day use.

Fig. 10 is an elevation of the rear of the board showing the electro-magnetic switch 60 for operating the shutter,

Fig. 11 is a perspective view of the rotatable shutter employed in connection with the character units illustrated in Fig. 9,

Fig. 12 is a diagrammatic view illustrating the connection of the correcting mechanism with four of the character frames, this correcting mechanism being embodied in the transmitter as illustrated in Fig. 1,

Fig. 13 is a detail cross section of the correcting mechanism, and

Fig. 14 is an elevation of a portion of the bulletin board, showing a modified arrangement of the reflectors in one of the character frames.

In order that a clear understanding of the invention may be gotten, the various elements of the invention will be described in detail in regular order. The invention consists principally of a night or a day 80 board, with a transmitter located at a distance from the bulletin board capable of being operated like a typewriter and arranged to actuate the character forming units on either the night or the day board. The first then in the order of description is

The night board.

The bulletin board 1 which in all of the views of the drawings with the exception of Figs. 9 *et. seq.* is arranged as a night board, consists of a row of character frames, 2, 3, 4, 5, etc., as illustrated in Fig. 1. The bulletin board may be made long enough to accommodate as many of the character frames as may be required. Provision is made in the drawings *i. e.* on the transmitter, for 19 character frames.

Each character frame consists of a wooden or metal box arranged in any suitable manner, holding 31 oblong reflectors 6 in the relative positions illustrated in Fig. 4. The reflectors 6 are made in two sizes as clearly shown in Fig. 4, and certain ones of the reflectors are disposed at various angles with respect to the vertical axis of the bulletin board for the definite purpose of the more perfect formation of a character.

The shape of each reflector is preferably

a compromise between an ellipse and a diamond. Each reflector consists of a single body substantially as shown in the drawings, which is made of any suitable material 5 for the purpose. The lamp units in which the reflectors are included, are thirty-one in number in each of the character frames 2 etc., as formerly stated, and for the purpose of future reference in the specification, 10 are numbered from 1 to 31 inclusive in Figs. 2 and 4.

Referring again to the peculiar disposition of the reflectors 6 in the character frames, it is intended that all reflectors 15 should be located exactly symmetrically with reference to a vertical axis through the frame and also with reference to a horizontal axis through the frame. In other words, the sets of reflectors on each side of 20 a center line drawn through one of the character frames, will bear the same relationship to the center line. It is to be observed that reflector #5 is at a greater angle from the vertical than reflector #8. The reflector 25 #2 is preferably slightly higher than reflector #1.

In the description to follow, reference will be made as an example, to the formation of the character "E". The character units 30 necessary to be lighted to form the character "E" on the night board are as follows: E— 1, 5, 8, 14, 19, 25, 28, 2, 3, 4, 15, 16, 17, 29, 30, 31.

The electro-magnetic switch.

For each reflector there is an electro-magnetic switch S_w . The operation of a particular set of the electro-magnetic switches S_w effects the lighting of a companion set 40 of the character units 6 to outline or form the entire character in one of the character frames 2. The operation of the electro-magnetic switch S_w is governed by the energization of a companion relay R of which 45 there is one for each switch. The energization of the relay R is entirely controlled by the mechanism of the transmitter T as will be explained under the description of the transmitter.

50 Since the construction of all of the switches S_w is alike, attention is directed to Fig. 3 wherein the construction of one is illustrated. Both the switch and the companion relay are mounted on an insulating 55 block 9 which is secured in any suitable manner and in any suitable position on the bulletin board 1 in back of the reflectors. Such details of construction as incasing the switches to protect them from the weather, 60 are obvious expedient which will be effected in actual practice and need not be described in detail at this time.

Pivoted on the diagonally extending portion of a stop bracket 10, is an external circuit switch arm 11. The arm 11 has a fin-

ger 12 which is held in engagement with a stop on the bracket 10 by a spring 13. The switch arm 11 rocks on its pivot against the tension of the spring 13 when an armature 14 on the lower end of the arm 11 is attracted upon the energization of a double-wound electro-magnet M .

The electric lamp 8 is lighted when the switch arm 11 moves over as just described, at which time a contact point 15 on the 75 switch arm 11 engages the external circuit contacts 16 on the block 9. The positive and negative external circuit wires 17 have branches 17^a and 17^c that lead to one of the contacts 16 and to the lamp respectively. 80 Another branch 17^b connects the other terminal of the lamp 8 with the other contact 16 and when the contact point 15 engages the two contacts 16, the circuit is completed and the lamp 8 is lighted as just described. The 85 same operation follows for each of the lamps 8 in a certain set designed to be lighted on one of the character frames 2, there being individual branches to each of the switches S_w from the positive and negative external circuit wires 17 as is clearly 90 shown in Fig. 2.

The contact point 15 has a swiveled mounting on the switch arm 11 in order that the point may adapt itself more readily to the contacts 16. In this connection it may be stated that the contact points 16 will in actual practice be located on the block 9 at right angles to the position illustrated in Fig. 3. This, however, is a minor 100 detail. The double-wound electro-magnet M includes pairs of coils M' and M^2 . These pairs of coils are capable of separate excitation. A primary exciting current flows through the pair of coils M' and is discontinuous, and a secondary exciting current flows through the coils M^2 and is continuous.

A circuit holding arm 18 is pivoted at 19 to a bracket 20 near the bottom of the block 10. A spring 21 normally holds the arm 18 against a stop 22 on the bracket 20 and out of engagement with an insulated contact 23. The head of the holding arm 18 is attracted to the electro-magnet M on the completion 115 of the primary circuit through the pair of coils M' at which time, the armature 14 is also attracted, and thus automatically closes the secondary circuit through the second set of coils M^2 by engaging the contact 23. The 120 flow of the primary current is established in certain of the switches S_w in the character frames 2, 3, etc. in succession by the simple act of depressing the keys of the transmitter; this primary circuit discontinues as 125 soon as the key is released. Both the secondary and primary circuits are fully traced below.

The secondary current in the same switches S_w is automatically established 130

upon the attraction of the holding arms 18 in each of the character frames in succession and flows continuously for each of the frames maintaining those lamps 8 which are lighted to form the character in each of the frames, until the whole line is written. The relay R has a pivoted armature 24 which is normally held out of engagement with the contact 25 by a spring 26. The armature 24 and contact 25 are in the primary circuit which embraces the coil M', previously referred to. The primary circuit is broken at the contact 25 when the relay R is deenergized. Similarly, the primary circuit is completed when the relay R is energized by the arrival of the roller 57 in Fig. 3, on the first plate 58. The primary circuit then is established from the battery B, through switch 61, 62, over positive wire W, cylinder C, bar 40, wire 41, armature 24, wire R^s, coils M', negative wire N', back to battery.

The transmitter.

The transmitter T has a keyboard K very much on the order of the keyboard of a standard typewriter. In Fig. 1 the keyboard K is shown to consist of 35 keys, although the number may be larger or smaller as conditions may dictate. Each of the keys K is pivoted on a common pivot rod 27 and has an arm 28 as shown in Fig. 8, to which one end of a flexible cable 29 of each key K is secured.

The cable 29 passes through a smooth hole in a guide bar 30 and from thence rearwardly, where it is fastened in the groove of a pulley 31 on the shaft 32 of a character cylinder C.

In the present instance, there are 35 of the character cylinders C to correspond to the number of the keys K of the keyboard of the transmitter T. The particular arrangement of the character cylinders on the transmitter is a matter that remains for future solution, there being a number of ways in which they may be mounted. In Fig. 1, however, they are shown as being divided; 18 character cylinders on one side and 17 on the other.

When a key K is depressed, the corresponding character cylinder C is rotated toward the observer and thus brings certain contacts into action to light the lamps in one of the character frames on the bulletin board to form the character corresponding to the key that was depressed.

Since all of the character cylinders C are precisely alike, the description of the one illustrated in Figs. 3, 6, and 7 will suffice for all. The character cylinder C includes a metal half 33 and an insulating half 34. The character cylinder may be assembled in any desired manner in order to be mechanically strong enough for the purpose for which it is intended and in this connection it is to

be noted that the metal and insulating segments of the cylinder are about equal in length. The metal segment 33 forms a common contact and has an advance contact 35 at one end for the purpose of performing the early operation of an escapement magnet E.

The character cylinder C has a stub shaft 36 at the end opposite the pulley 31, which is mounted in a suitable bearing 37. The bearing 37 becomes a common ground connection for a positive extinguishing wire W which leads to the positive pole of the battery B. A spring 38 attached at the respective ends to the bearing 37 and to the cylinder C, serves to return the character cylinder to the normal position when the key K which controls the cylinder, is again released after depression. This spring 38 keeps the cable 29 taut.

A plurality of character wire bars 40 are mounted at their respective ends on insulating supports 39. There are thirty-one of the character wire bars 40 on each side of the transmitter T in Fig. 1; there is one character wire bar 40 for each of the character units 6 in each of the character frames on the bulletin board. Consequently, thirty-one wires run from the character wire bars 40 to the bulletin board 1 where each individual wire is branched off to the same individual one of the character units 6. These wires leading from the character wire bars 40 are termed the common character wires 41.

In order to illustrate this point more clearly, it is to be observed in Fig. 1 that the common character wires 41 which are thirty-one in number, leave the transmitter T in a bundle and lead to the bulletin board 1. The divided arrangement of the character wire bars on the respective sides of the transmitter, makes it necessary to fork the corresponding ones of the character wire bars on the right side to the common character wires 41 of the character wire bars on the left side. The first ten bars on each side in Fig. 1, are numbered "1" to "10" inclusive. The character wire emerging from the bar "1" is common to each character unit #1 on the bulletin board.

Similarly, the wire emerging from the character wire bar "2" is common to all of the character units #2 on the bulletin board so that there are bundles of branch wires f, g, h and i leading from the common character wires 41 to each of the character frames 2, 3, 4, 5, etc.

There is an escapement contact bar 42 which is similar in all respects to the character wire bars 40, on each of the banks of bars on either side of the transmitter. The contact rollers 45 (shown in Fig. 6) of the escapement contact bar 42 complete a circuit through the escapement magnet E every 130

time one of the character cylinders C is rotated upon the depression of a key on the keyboard. This circuit (shown in Fig. 1) is completed from the positive pole of the battery B, over wire W, contacts 33, 35 of cylinder C, roller 45, wire 53^a, magnet E, negative wire 54, back to battery. Each of the character wire bars 40 has a non-circular opening 43 directly above each of the character cylinders C which extend at right angles to the character wire bars.

The non-circular shank 44 of a contact roller 45 is arranged to be inserted in certain of the openings 43, where it is held by a cotter pin 46 at the top. A spring 47 on the shank 44 is so disposed as to bear the contact roller 45 into firm engagement with the surface of the character cylinder C. Only those of the character wire bars 40 wherein the openings 43 in a transverse line across the character wire bars, *i. e.* above a particular one of the character cylinders C, are occupied by the shanks of the contact rollers 45, become active to light the lamps in one of the character frames represented by the character cylinder just mentioned.

The carriage and escapement.

The escapement magnet E may be repeatedly energized to space the carriage 48 across the transmitter T, by operating the space bar 49 very much on the order of the ordinary typewriter. A positive wire 50 leads from the extinguishing wire W to a contact 51 on the space bar 49. The circuit which embraces the extinguishing wire W is arranged to be broken by means of a circuit breaking key 61 which will be described later. A contact 52 is arranged to be engaged by the contact 51 upon the depression of the bar 49, and when this occurs, current flows from the battery B, over the wire 50, over the spacer wire 53 to the escapement magnet E and back to the battery through the negative wire 54.

An armature 55 is attracted by the energization of the magnet E, and the upward movement of the armature 55 causes the operation of the escapement mechanism 56, thus advancing the carriage 48 one step farther toward the left. This escapement mechanism is a part of any particular typewriter that might be adopted, and for the purpose of understanding the invention, it is sufficient to designate only a part as shown in Fig. 5. The escapement magnet E is also energized by means of the advance contact 55 on each of the character cylinders C, when any one of the keys K is depressed. Under such circumstances, current flows from the positive pole of the battery B, over the extinguishing wire W, through the metal portions of the particular character cylinder which is being rotated by the depression of

the key and on the initial portion of said rotational movement, to the advance contact 55, through one of the engaging contact rollers 45 on the escapement contact bar 42, over the portion 53^a of the spacer wire 53 to the escapement magnet E and from thence back to the battery. These actions occur on the initial rotational movement of the character cylinder as just stated, and upon the continued depression of the same transmitter key K, the character cylinder is completely rotated to position, whereupon the corresponding character is lighted on one of the character frames.

All thirty-one of the relays R of the individual character frames on the bulletin board are energized and deenergized in succession as the carriage 48 traverses the transmitter T. This successive energization and deenergization is accomplished through the successive engagement of a carriage roller contact 57 with the isolated contact plates 58^a, 58^b, 58^c and 58^d, etc., of a relay contact bar 58. The isolated plates are separated by strips of insulating material 59. The contact bar 58 is provided with means 58^m whereby it can be adjusted longitudinally to compensate for any inaccurate registration of the roller 57 and the plates 58^a, 58^b, etc. The means 58^m is countersunk at 58^m to bring it flush with the top of the bar, (see Fig. 2). The roller contact 57 is mounted on the carriage 48 from which it is insulated as illustrated, and is connected to the extinguishing wire W by a wire 60 or some other suitably arranged connection which will accommodate itself to the movement of the carriage across the transmitter.

There are nineteen of the isolated contact plates on the relay contact bar 58; one plate for each of the character frames on the bulletin board 1. The first contact plate 58^a is connected through a common relay wire R' to all of the relays R in the first character frame 2. Similarly, the second, third and fourth isolated plates 58^b, 58^c, and 58^d are connected through common relay wires R², R³ and R⁴ with the second, third and fourth character frames 3, 4 and 5. The remaining isolated plates on the relay contact bar 58 are similarly connected with the remaining character frames on the bulletin board, but the illustration has been omitted since the operation can be fully understood by considering the first four character frames. The roller 57 having moved upon the isolated contact plate 58^a in the first step, current flows from the positive pole of the battery B over wire W, switch 61, 62, branch 60 in Fig. 3 through the roller 57 and the plate in contact therewith, over the first common relay wire R', through each of the relays R in the first character frame 2, and back to the battery B through the negative wire N.

which is common to both the relays and switches S_w in all of the frames of the bulletin board.

The correcting mechanism.

5 Fixed on the transmitter T is a bar 72 of insulating material and a rod 73 of good conducting material. The bar and rod are parallel to the relay contact bar 58 as plainly shown in Fig. 12. The ends of the conducting rod 73 are fixed in insulating sockets 74. A plurality of spring contact fingers 75 are fixed on the insulating bar 72 and bear up against the conducting rod 73.

10 The ends of the fingers 75 project beyond the rod 73 a sufficient distance to enable the operation of the correcting roller 76. The number of the contact fingers 75 corresponds to that of the relay contact plates 20 with which they align. Accordingly, in the present instance, there are nineteen of the spring contact fingers 75.

15 An arm 77 has a suitable bearing in the end in which the non-conducting correcting roller 76 is journaled. A finger piece 78 enables the depression of the arm 77 so as to cause the roller 76 to bear down on the spring contact fingers 75 directly therebeneath, and break the circuit then completed through 25 this particular contact finger and the conducting rod 73. This action causes the extinction of all of the lights on the companion character frame for the reason that the circuit then established from the positive pole 30 of the battery, over wire W , (see Fig. 3), rod 73, finger 75, wire W' , coils M^2 of the magnet M , arm 18 then in engagement with contact 23, negative wire N' , back to battery, is broken at 73, 75 in Fig. 13.

40 A pivotal mounting 79 enables the depression of the arm 77. The pivot block 80 which is mounted beneath the insulating support of the roller 57, carries a spring 81 which normally keeps the correcting roller 45 76 out of contact with the spring contact fingers 75 and keeps the stop 82 against the bottom of the arcuate recess 83 in the block 80, which limits the movement of the arm 77.

The wiring.

50 The extinguishing wire W is a positive wire which leads from the positive pole of the battery B , and is common to all of the character cylinders C as clearly shown in Fig. 1. The extinguishing wire W is so called, because the function thereof is to interrupt or break the continuous and secondary current flowing through the pair of coils M^2 , upon the return of the carriage 48 to the original position at the right of the transmitter, at the completion of the writing of the line. For this purpose, the circuit breaking key 61 is introduced in the wire W .

55 The key 61 may be of any suitable construction, although in the present instance,

it is shown to be a spring-like member normally bearing against a coacting contact 62 in the wire W . The key 61 has an insulating head 63 which the carriage 48 is adapted to strike upon being returned to the right 70 as shown in Fig. 3. When this is done, the current flowing from the battery B is interrupted with the result above mentioned.

The circuit breaking key 61 automatically breaks the circuit through the extinguishing wire W through the engagement of the carriage 48, or if it becomes necessary the "end of line" key 84 may be employed to break the circuit manually. The arrangement of the circuit breaking mechanism in the wire 75 W is largely shown diagrammatically and the actual construction thereof is a matter which is left for future development.

80 Returning again to the wiring, a branch of the extinguishing wire W beyond the circuit breaking key is connected to the conducting rod 73. Positive wires W' , W^2 , W^3 , W^4 , etc., connect the successive spring contact fingers 75 with the successive character frames on the bulletin board 90 1. For example, the first finger 75 has the wire W' which reaches to the first character frame 2. The second contact finger 75 has the wire W^2 which reaches to the second character frame 3, and so on. This arrangement is illustrated in Fig. 12.

95 After the first wire W' reaches the first character frame, it is divided into a number of branches which are connected to each of the coils M^2 of all of the electro-magnetic switches S_w of the character frame. This is shown in Fig. 2. A single connection is 100 shown in Fig. 3. The second wire W^2 is similarly connected to each of the coils M^2 of all of the electro-magnetic switches S_w on the second character frame, and so on. The secondary and continuous circuit through the coils M^2 which keep the armature 14 attracted and corresponding ones of the character forming units illuminated 110 while the remainder of the line is written, may be broken in any of the character frames by simply moving the correcting roller 76 over the desired one of the spring contact fingers 75 and pressing down thereon. This 115 separates the contact finger from the conducting rod 73 and breaks the circuit in the particular wire leading from the spring contact.

120 Positive branches R^6 lead from the relay contact 25 to the coils M' . The current returns from the battery B from both pairs of coils M' and M^2 through negative branch wires N' . The negative branches N' all connect to the common negative return wire N which leads to the negative pole of the battery B .

125 The branch wires f , g , h , i , etc. leading from the common character wires 41 are all positive wires. Each of the branch wires f 130

of the first character frame 2 for instance, connect one of the thirty-one common character wires 41 with the pivotal point of the armature 24 of the relay R of the character unit 6 having a corresponding number. In each instance, the branch wires f lead to the pivotal point of the armature 24. To illustrate: the first of the branch wires f leads from the first common character wire of the bar "1" to the armature 24 of the character unit #1. The second branch wire leads from the common character wire of the bar "2" to the armature of the character unit #2, and so on for each of the thirty-one character units and character wire bars.

Relay wires R', R², R³, R⁴, etc., are severally common to the first, second, third, fourth, etc., character frames. That is to say, the relay wire R' leads from the first metal contact plate 58^a on the relay contact bar 58 to the first character frame where it branches out into positive branches R^a which are common to all of the relays in the first frame. The current returns via the common negative return N to the battery B, through the negative branches N^a. When the roller contact 57 rests on the first plate 58^a, all of the relays R of the first frame only are energized as previously explained. When the roller 30 moves over to the second plate 58^b, all of the relays R in the second frame are energized, while the relays R in the first frame become deenergized. The same successive energization and deenergization of the relays R occurs throughout the length of the bulletin board as the carriage 48 traverses the transmitter T and the roller contact 57 progresses over the relay contact bar 58.

Formation of the character "E."

Let it be desired to illuminate the first part of a message "ever send ships to" on the bulletin board 1. The key K bearing the character "E" on the transmitter T is depressed. On the initial portion of the rotational movement of the character cylinder C which is connected to this key, the advance contact 35 moves into engagement with the contact roller 45 of the escapement contact bar 42 and current instantly flows from the positive pole of the battery B, over the common positive wire W, into the connection at the left of the cylinder C, to the metal portion 33 of the cylinder to the advance contact 35, through the engaging roller 45 and escapement contact bar 42, over the wire 53^a to the escapement magnet E, and back to the common negative wire N over the wire 54. The escapement magnet E being thus energized, attracts the armature 55 which operates the escapement and brings the carriage 48 over one step and the roller contact 57 into engagement with the first plate 58^a of the relay contact bar 58.

Instantly upon engagement of the roller

contact 57 with the first plate 58^a, current flows from the positive pole of the battery B over wire W through switch 61, 62, and wire 60 to the roller 57, through the plate 58^a, over the relay wire R', over the positive relay branches R^a to each of the relays R, energizing the relays and returning to the common negative wire N through the negative branches N^a. All of the armatures 24 of the first frame are thus attracted and brought into engagement with the contacts 25.

This all happens on the initial movement of the key "E" and the corresponding character cylinder C. Upon continued depression of the key "E" the metallic segment 33 moves beneath and into engagement with those of the contact rollers 45 of the character wire bars 40 which occupy the proper openings 43 transversely of the transmitter and above the character cylinder C just rotated into full position. Current now flows from the positive pole of the battery B, through switch 61, 62, and over the common positive wire W out of those of the character wire bars 40 which have contact rollers 45 in engagement with the metal segment 33 of the character cylinder C. The formation of the character "E" requires the lighting of the following lamps: 1, 5, 8, 14, 19, 25, 28, 2, 3, 4, 15, 16, 17, 29, 30 and 31, and the following is the action that takes place in the lighting of lamp #1, the same action taking place in all others that make up the character "E."

Current now flows from the battery B through switch 61, 62, over positive wire W into the character cylinder C at the left, through the contact roller 45 of the character wire bar "1," out of the bar over the common character wire 41 connected therewith, over the first wire of the branch f to the pivot of the armature 24 which is now in engagement with the contact 25 by reason of the energization of the relay R, over the wire R^a, through the pair of coils M' and back to the battery via the negative branch N'. This is the primary circuit which energizes the electro-magnet M of the switch Sw and is discontinuous or temporary in duration.

The coils M' of the electro-magnet M having been energized, the armature 14 of the arm 11 is attracted, causing the closure of the external circuit through the lamp 8 of the character unit #1, comprising positive wire 17, branch 17^a, contacts 16 (see Fig. 3), wire 17^b, lamp 8, wire 17^c, back to the negative wire 17, and consequently lighting the lamp. The head of the circuit-holding arm 18 is also attracted to the electro-magnet M with the armature 14. This causes the closure of the secondary and continuous circuit by the engagement of the lower portion of the arm with the contact 23,

This contact having been made, current now flows from the positive pole of the battery B, over the branch of the common positive wire W to the conducting rod 73, through the first spring contact finger 75, over the wire W' and all of the branches thereof in the first character frame, through the second pair of coils M² of the electro-magnet M, through contact 23 and arm 18 to the pivotal point 19 and back to the battery through the negative branch N'. The electro-magnet M is thus practically again energized by virtue of the secondary current flowing therethrough, and it thereby holds the armature 14 and head of the holding arm 18 in contact therewith until the whole line is written on the bulletin board. It should be observed that under normal conditions the wires W', W², W³, W⁴, etc., are not energized since the circuit holding arms 18 are normally out of contact with the points 23 which must be engaged by the arms in order to complete the secondary circuit.

When the next key on the transmitter keyboard is struck to form the next character on the bulletin board, the roller contact 57 is made to advance to the next plate 58^b in the manner already described, consequently breaking the original circuit flowing through the first relay wire R', causing the lifting of all of the armatures 24 of the first frame 2 by virtue of the springs 26, and breaking the primary circuit which up to this time flows through the first pair of magnet coils M'.

The flow of current having once been established in the wire W' etc., it follows that the holding arm 18 is automatically held into the contact making position and automatically holds the secondary circuit so that the lamp 8 of the character unit #1 remains lighted until the carriage 48 is returned to the original position at the right. When this occurs, the circuit breaking key 61 is struck, opening the circuit in the common positive wire W and consequently breaking the flow of current through the second pair of coils M² of all of the character frames and allowing the arms 11 and 18 to return to their original positions by virtue of the springs 13 and 21 respectively.

By means of the correcting mechanism, the transmitter carriage may be conveyed to any desired point and the finger piece 78 depressed to cause the breaking of the circuit through any single one of the character frames on the illuminated bulletin board. If desired, the finger piece 78 may be held down until the carriage 48 is moved backwardly the required distance to obtain the extinction of all of the characters up the point where the correction is to be made.

The action that takes place in lighting 65 one of the lamps 8, takes place in the light-

ing of each of the lamps 8 for the formation of the entire character "E." Obviously, where a contact roller 45 is omitted from a character wire bar 40 crosswise of the bank of character wire bars, no current will flow 70 through that character wire bar and to the corresponding lamp in the character frame. Thus, any opening that may be vacant above the character cylinder which is rotated by depression of a key on the transmitter key-board, will indicate that the corresponding lamp in the character frame which is then active remains dark.

The day board.

80

In the day board the same arrangement obtains as in the case of the night board, but in place of the reflectors and lamps, an arrangement of shutters is provided which makes the letters appear in white against 85 the bulletin board which in this instance is black. The arrangement of one of the character units is illustrated in Figs. 9, 10 and 11, wherein it will be observed that a shutter 64 has a ball bearing mounting 65 on a 90 spindle 66 which projects on the back of the bulletin board 1. The shutter 64 has alternating black and white stripes radiating from the center.

The black stripes normally coincide with 95 slots 67 which radiate from the center substantially as shown in Fig. 9. The shutter 64 is held in this position by a spring 68 which holds one side of a notch 69 in the periphery of the shutter against a stop pin 70. 100 The shutter 64 has a pivoted armature 14^a on the back which is arranged to be attracted upon energization of the electro-magnet M of the electro-magnetic switch Sw precisely in the manner formerly explained. 105 In all respects, the operation of the switch Sw shown in Fig. 10 is the same, and the day board is operated from the transmitter T in exactly the same manner as is the night board. The advantage of providing the plurality of apertures 67 which correspond to the reflectors 7 of the character units 6 formerly referred to, is that the shutter 64 need rotate only through a very small arc in order 110 to bring the white stripe into registration with the apertures for the formation of the character. Incidentally, the shutter may be balanced with pieces of iron so that it may be perfectly free to rotate on its bearing and 115 respond quickly to the electro-magnet M.

120

Review of the operation.

From the foregoing description, the manner of operating the electric bulletin will be readily understood. A transmitter T is located in a room possibly some distance from the bulletin board 1, and the two are connected together in the present instance by seventy wires. Thirty-one of these are the common character wires 41, nineteen positive 130

wires W' , W^2 , W^3 , W^4 , etc., nineteen positive individual relay wires R' , R^2 , R^3 , R^4 , etc., and one common negative return wire N .

The fact that nineteen character frames 5 on the bulletin board are herein specified, must not cause confusion. There may be as many character frames on the bulletin board as may be desired. The number of the frames will of course be governed by the 10 length of the portion of the message it is desired to light up on the board, and the number of wires extending from the transmitter will be increased accordingly.

The carriage 48 has the principal function 15 of carrying the roller contact 57 which runs across the stationary relay contact bar 58. Since it has no other function, it becomes convenient to use the platen for the holding 20 of the message. The message is written on a piece of paper and inserted in the carriage, where a line at a time appears in the opening of a guard or shield G. When the one line is written, the platen is turned to bring the next line into appearance and the shield 25 thus makes it easy for the operator to follow the message he desires to transmit.

Now to transmit the message, the keys K are struck in regular order after the manner 30 of operation of the ordinary typewriter. On depressing the key "E," the character units illustrated in Fig. 2 and formerly enumerated, are instantly lighted. The escapement magnet E is operated on the initial portion 35 of the key "E" so as to advance the carriage 48 one step and bring the roller contact 57 into engagement with the first plate 58^a. The first character being lighted, the next key "V" is struck, whereupon the following character units are lighted in the second 40 frame 3; 1, 9, 15, 21, 26, 22, 17, 12 and 4.

Should it be desired to skip the third character frame in order to make the space, the space bar 49 is depressed when the escapement magnet E is actuated and no character 45 is formed in the third frame. The same operation in forming the characters follows throughout the length of the line and when the whole line is written, the carriage 48 is returned to the original position.

50 The modification in Fig. 14 consists simply of an improved arrangement of the units 6 in each of the character forming groups. It will be observed that thirty-two of the units are employed. The units as 55 here arranged, it is believed will secure a more perfect formation of the characters.

While the construction and arrangement 60 of the electric bulletin board as herein described, is that of a generally preferred form, obviously modifications and changes may be made without departing from the spirit of the invention or the scope of the claims.

I claim:

65 1. A bulletin comprising a bulletin board

having a group of character forming units including lamps, a transmitter for operating the bulletin in electrical communication therewith, an electro-magnetically operated circuit closing switch for the lamp of each 70 unit, means including a key-operated contact cylinder and contact bars, embodied in the transmitter for completing a primary discontinuous circuit through said switch to obtain the lighting of a set of said lamps to 75 form a character, and self contained automatically operating means embodied in said switch for completing a secondary and continuous circuit therethrough to keep said set of lamps lighted.

2. A bulletin comprising a bulletin board having a row of groups of character forming units including lamps, an electro-magnetically operated external circuit closing switch for each lamp, a relay controlling a 85 primary and discontinuous circuit through the electro-magnet of each of said switches, a transmitter including a row of insulated contact plates, each in electrical connection with the groups of relays of the several 90 groups of units, a movable contact maker arranged to traverse said plates, and energize and deenergize said groups of relays in succession along the board, a key, a rotatable contact member brought into active 95 position upon depression of the key, and a fixed coöperating contact member arranged to complete said primary circuit through the electro-magnet of said external circuit closing switch upon the depression 100 of said key.

3. A bulletin comprising a bulletin board having a row of groups of character forming units including lamps, an electro-magnetically operated external circuit closing 05 switch for each lamp, a relay controlling a primary and discontinuous circuit through the electro-magnet of each of said switches, a transmitter including a row of insulated contact plates, each in electrical connection with the groups of relays of the several 110 groups of units, a movable contact maker arranged to traverse said plates and energize and deenergize said groups of relays in succession along the board, a key, a rotatable contact member brought into active 115 position upon depression of the key, a fixed coöperating contact member arranged to complete said primary circuit through the electro-magnet of said external circuit closing switch upon the depression of said key, and means for advancing the traversing contact maker one step upon the initial depression of a key and the initial rotation of the corresponding rotatable contact member. 120

4. A bulletin comprising a bulletin board having a row of groups of character forming units including lamps, an electro-magnetically operated external circuit closing switch for each lamp, a relay controlling a 130

- primary and discontinuous circuit through the electro-magnet of each of said switches, a transmitter including a row of insulated contact plates, each in electrical connection with the groups of relays of the several groups of units, a movable contact maker arranged to traverse said plates and energize and deenergize said groups of relays in succession along the board, a key, a rotatable contact member brought into active position upon depression of the key, a fixed co-operating contact member arranged to complete said primary circuit through the electro-magnet of said external circuit closing switch upon the depression of said key, means for advancing the traversing contact maker one step upon the initial depression of a key and the initial rotation of the corresponding rotatable contact member, and means for returning the rotatable contact member upon the release of the key.
5. A bulletin comprising a bulletin board having a group of character forming units including lamps, an external circuit closing switch for each of the lamps, a double wound electro-magnet for operating the switch, a relay for each switch having an armature controlling a primary circuit through one of the coils, a transmitter including an insulated contact plate in connection with the relay, a traversing contact member arranged to complete the circuit through the relay to attract the armature, a rotatable character cylinder including a contact embodied in the transmitter, a character wire bar having a co-operating contact engaging said contact upon rotation of the cylinder, electrical connections including the relay armature for completing the primary circuit through one of said electro-magnet coils, and automatically acting means simultaneously attracted to the electro-magnet with the external circuit closing switch, for completing a secondary and continuous circuit through the second coil.
6. A bulletin comprising a bulletin board having a group of character forming units including lamps, an external circuit closing switch for each of the lamps, a double wound electro-magnet for operating the switch, a relay for each switch having an armature controlling a primary circuit through one of the coils, a transmitter including an insulated contact plate in connection with the relay, a traversing contact member arranged to complete the circuit through the relay to attract the armature, a rotatable character cylinder including a contact embodied in the transmitter, a character wire bar having a co-operating contact engaging said contact upon rotation of the cylinder, electrical connections including the relay armature for completing the primary circuit through one of said electro-magnet coils, automatically acting means simultaneously attracted to the electro-magnet with the external circuit closing switch, for completing a secondary and continuous circuit through the second coil.
7. A bulletin including character units arranged to outline visible characters, a transmitter enabling the selective formation of the characters including a fixed relay contact bar having insulated plates, a traversing contact maker arranged to move over the plates, a key, a rotatable character cylinder connected to the key, said cylinder including an insulated portion and a contact portion having an advanced contact, character wire bars each in electrical connection with one of said units and arranged to coact with said contact portion, an escapement contact bar arranged to coact with said advanced contact, and escapement mechanism arranged to be electrically operated by the prior engagement of said advanced contact with the escapement contact bar, on the initial depression of said key to move the traversing contact forward one step.
8. A bulletin comprising a bulletin board having a group of character forming units including lamps, a transmitter arranged to light certain of said lamps to form a character, including a depressible key, a character cylinder including an insulating portion and a contact making portion, means connecting the cylinder with the key for rotating the cylinder upon depression of the key, a plurality of character wire bars spaced from the character cylinder and each having a non-circular opening, electrical connections between said bars and the operating mechanism of corresponding ones of said lamps, contact members occupying said openings, means bearing said contact members of said cylinder, and an electrical connection leading to the contact portion of said cylinder.
9. The combination of a character wire bar having a plurality of non-circular openings, a plurality of character cylinders including metallic contact portions disposed beneath said openings, and contact members insertible in said openings to bear on the cylinders beneath.
10. The combination of a character wire bar having a plurality of non-circular openings, a plurality of character cylinders including metallic contact portions disposed beneath said openings, contact members including non-circular shanks insertible in any of said openings, contact rollers carried by said shanks to bear on the cylinders, and means for pressing the rollers in contact.
11. A bulletin including a group of character forming units arranged to define a character, an electro-magnet initially oper-

- ative by a primary and discontinuous circuit, a movable member attracted by said magnet and arranged to actuate the corresponding one of said units, and a pivoted arm attracted simultaneously and arranged to automatically complete a secondary circuit through the magnet to hold said member against the magnet. 5
12. A bulletin including a group of character forming units arranged to define a character, an electro-magnet initially operative by a primary and discontinuous circuit, a movable member attracted by said magnet and arranged to actuate the corresponding one of said units, a pivoted arm attracted simultaneously and arranged to automatically complete a secondary circuit through the magnet to hold said member against the magnet, and means including a spring normally holding said member out of engagement with the magnet. 10
13. A bulletin including a group of character forming units arranged to define a character, an electro-magnet initially operative by a primary and discontinuous circuit, a movable member attracted by said magnet and arranged to actuate the corresponding one of said units, a pivoted arm attracted simultaneously and arranged to automatically complete a secondary circuit through the magnet to hold said member against the magnet, means including a spring normally holding said member out of engagement with the magnet, and means including a spring normally holding said pivoted arm in the inactive position. 15
14. In an electric bulletin, a series of character forming groups composed of lamps arranged to be lighted, individual operating means for each lamp, a transmitter for controlling the operation of said means in each group in the formation of a character, said transmitter including a depressible key, contact making means actuated by each key and arranged to selectively light certain of the lamps in a group to form a character, a step-by-step advancing contact maker initially rendering each group sensitive in succession for the subsequent formation of a character by means of the key, means including a conducting rod and spring contact in normal engagement, forming a part of a continuous circuit keeping the lamps of a formed character lighted 20 during the writing of a line, and means as- 25
- sociated with said step-by-step contact maker enabling the separation of any one of said spring contacts from said conducting rod to extinguish the corresponding character for correction. 30
15. In an electric bulletin, a bulletin board having a group of character forming units including lamps, an electro-magnetically operated circuit closing switch for the lamp of each unit, an operating transmitter embodying means for sending a primary discontinuous circuit through said switch to obtain the lighting of a set of lamps to form a character, self-contained automatically operating means embodied in each switch 35 for sending a secondary and continuous circuit therethrough to keep said set of lamps lighted while the remainder of the line is written, and associated means embodied in the transmitter enabling the extinction of 40 any one of the previously formed characters for the purpose of correction. 45
16. In an electric bulletin, a transmitter including a traversing carriage with a contact maker, an electro-magnetically actuated space-bar control escapement mechanism for said carriage, and a relatively stationary contact bar having a plurality of contacts insulated from each other and arranged to be engaged in succession by the contact 50 maker as the carriage traverses the transmitter. 55
17. The transmitter of claim 16, further characterized by the provision of means for adjusting the contact bar beneath the contact 60 maker. 65
18. The combination, of a half insulation and metal character cylinder rotatably mounted, a plurality of character wire bars in spaced relationship above and at right 70 angles, and contact members pendent from predetermined ones of the character wire bars adapted to engage said metal half upon rotation of the cylinder. 75
19. The combination in a device for disseminating intelligence, consisting of a bulletin board having a series of character forming groups, means for successively rendering characters visible in the series of groups, including a transmitter having a traversing member, and means associated with the latter and coöperating with a portion of said first mentioned means for rendering any character in any of said groups invisible. 80

RALPH ERNEST JONES.
